Inventor,

Wellington P. Kidder.

UNITED STATES PATENT OFFICE.

WELLINGTON P. KIDDER, OF MALDEN, MASSACHUSETTS.

COMBINATION OF DRAWING-TABLET AND INSTRUMENT-CASE.

SPECIFICATION forming part of Letters Patent No. 284,131, dated August 28, 1883.

Application filed October 27, 1882. (No model.)

To all whom it may concern:

Be it known that I, WELLINGTON P. KIDDER, a citizen of the United States, residing at Malden, in the county of Middlesex and State of Massachusetts, have invented certain new and useful Improvements in Drawing Tablets and Instruments, whereby the parts are combined in convenient form to be easily carried in an ordinary pocket and used at any time, of which the following is a specification.

The object of my invention is to provide mechanical draftsmen, engineers, machinists, artists, and students with portable materials, such as are useful in making drawings and sketches of many kinds, combining the materials in an improved and compact form.

My device consists of a block of sheets of paper secured together on two or more sides or edges in the ordinary and well-known form of memorandum blocks or tablets, a back block, of wood or other suitable material, supporting in recesses an ordinary T-square, a pair of compasses, and a pencil. To one side of the block of wood is secured the block of paper. On the opposite side of the block of wood is engraved or printed an ordinary protractor or instrument for measuring angles, all of which will be readily understood from the accompanying drawings, in which—

Figure 1 is an edge view; Fig. 2, a plan of the side upon which the block of paper is attached; Fig. 3, a plan of the reverse side, showing the protractor; Fig. 4, an opposite edge view; Figs. 5 and 6, opposite end views; Fig. 7, a section of Fig. 2 on line A⁶ B⁶ of Fig. 1, showing the compasses, T-square, and pencil in their recesses in the block of wood before mentioned. Fig. 8 is a perspective view, showing the two blocks, one of paper and the other of wood, attached to each other, with the instruments, except the protractor, removed.

Similar letters and figures refer to similar parts throughout.

a represents the block of paper. It may be glued along its two edges a' a'', and glued to the block of wood B at a³.

B represents the block of wood or other material which supports the various instru-

ments. This block should be as thin as will give room for the instruments, and as light and strong as practicable. It may form a permanent part of the device, to which new blocks of sheets of paper may be secured as fast as the old sheets are used up; or it may, in practice, be cheaply gotten up, to be destroyed with the block of paper.

B' B² B³ represent the three recesses or pockets for receiving the compasses, T-square, and pencil.

C represents the compasses. They may be of any well-known and suitably-compact pattern.

D represents the T-square. This instrument is provided with the well-known swivel-head D', for transferring any desired angle of the protractor to the drawing. The T-square is also a scale accurately divided off into inches and fractions of inches, as indicated in Fig. 7. In practice I prefer eighths, tenths, twelfths, and fourteenths of inches, and their usual subdivisions, marked in the well-known manner.

The pencil E requires no description. On the reverse outside of the block B is an ordinary protractor, F, Fig. 3. This may be divided in the usual manner in a semicircle of one hundred and eighty degrees.

It is evident that my device might be arranged to open in book form, the block B containing the tools on one side and the block or sheets of paper on the other; or the two might be independent, either of which constitutes a part of my invention.

I do not claim a block of paper glued, as above, or the combination therewith of a pencil.

I claim—

The combination, substantially as herein-before set forth, of a block of sheets of paper, and a back block to which the block of sheets of paper is attached, the back block having recesses formed within it for the reception of drawing-instruments, substantially as and for the purposes specified.

WELLINGTON P. KIDDER.
